UNITED STATES PATENT OFFICE.

TRUMAN DEAN GARD, OF KOKOMO, INDIANA.

GASOLENE-VULCANIZER.

1,171,038.

Specification of Letters Patent.

Patented Feb. 8, 1916.

Application filed July 15, 1915. Serial No. 40,082.

To all whom it may concern:

Be it known that I, TRUMAN D. GARD, a citizen of the United States, residing at Kokomo, in the county of Howard and State 5 of Indiana, have invented a new and useful Gasolene-Vulcanizer, of which the following is a specification.

The device forming the subject matter of this application is a vulcanizer adapted to 10 be employed for repairing auto and motorcycle tires of any description.

One object of the present invention is to provide a device of this type which may be readily applied to the tire and with equal 15 facility be removed therefrom.

Another object of the invention is to provide a device of the type above indicated having resilient means for bringing the compression elements into coöperative relation 20 with respect to the article which is being mended, one of the compression elements being pivotally mounted.

The invention aims to improve generally and to enhance the utility of, devices of 25 that type to which the present invention appertains.

With the above and other objects in view which will appear as the description proceeds, the invention resides in the combination 30 and arrangement of parts and in the details of construction hereinafter described and claimed, it being understood that changes in the precise embodiment of the invention herein disclosed can be made 35 within the scope of what is claimed without departing from the spirit of the invention.

In the drawings:—Figure 1 shows the invention in side elevation; Fig. 2 is a top plan; Fig. 3 is a longitudinal section.

In the present embodiment of the invention, a pair of movably connected members are provided, one member being in the form of a base or primary lever 1, equipped adjacent one end with a laterally extended 45 supporting foot 2, the primary lever 1 adjacent its opposite end being broadened to form a compression member 3. Intermediate its ends, the primary lever 1 is provided with an ear 4 which is slotted as indicated at 5. One end of the lever 1 is equipped with an upstanding lug 6.

The secondary lever is denoted by the numeral 7 and intermediate its ends is provided with an ear 8 which registers in the 55 slot 5 of the ear 4 there being a pivot element 9 connecting the ears 8 and 4. There is

a lug 10 upon the lever 21. An arched compression spring 11 is interposed between the levers 1 and 7 and bears against the levers, adjacent their free ends, the spring 11 being 60 provided with openings receiving the lugs 6 and 10. As indicated at 21, the secondary lever 7 is arched throughout a portion of its length, transversely, to fit the hand of the user. In the lever 7 there may be formed an 65 opening 12, beyond which is located a transverse head 14 provided with approximately parallel arms 15.

Disposed between the arms 15 is a combined fuel receptacle and compression element 70 taking the form of a cup 16 provided with trunnions 17 which are pivoted in the arms 15. Upstanding from the bottom of the cup 16 are frusto-pyramidal pillars 18.

In practical operation, the free ends of the 75 levers 1 and 7 may be pressed together, putting the spring 11 under compression. In this manner, the cup 16 will be spaced apart from the compression element 3 of the primary lever 1 and the tire or other article 80 which is being mended may be placed between the cup 16 and the compression member 3. When pressure upon the free ends of the levers 1—7 is released, the spring 11 will cause relative movement between the 85 levers 1 and 7, the combined compression member and fuel receptacle 16 coöperating with the compression element 3 to exert a pressure upon the tire 20. At this point it is to be noted that owing to the pivotal 90 mounting of the cup 16, the same will co-operate properly with the compression element 3 under the action of the spring 11.

A quantity of fuel, preferably a volatile hydrocarbon, indicated at 19, is placed in the 95 cup 16 and is ignited. Thus the vulcanizing operation will be carried out, the pillars 18 serving to conduct the heat into the bottom of the cup 16.

Having thus described the invention, what 100 is claimed is:—

1. In a device of the class described, pivotally connected members, one member being provided with a compression element; a combined compression element and fuel 105 holder pivoted to the other member; and spring means engaged with the members to cause the compression elements to coact.

2. In a device of the class described, a pair of levers pivotally connected intermediate 110 their ends, one lever being provided at one end with a compression element, and the

other lever being provided at the corresponding end with a pivotally mounted fuel holder coöperating with the compression element; and a spring connecting the levers to cause the fuel holder and the compression element to coact.

3. In a device of the class described, a primary lever provided at one end with a compression element; a secondary lever provided at the corresponding end with spaced arms; a fuel holder pivoted in the arms and coöperating with the compression element; ears projecting from the levers intermediate their ends; a pivot element connecting the ears; and a compression spring interposed between the levers upon the opposite side of the ears from the compression element and the fuel holder.

4. A vulcanizer comprising a pair of pivotally connected members one of which is

provided with a compression element; and a combined compression element and fuel receptacle pivoted to the other member.

5. A vulcanizer comprising a pair of levers connected intermediate their ends, one of the levers at one end being provided with a compression element, and there being a combined compression element and fuel receptacle pivoted to the corresponding end of the other lever, the opposite ends of the levers constituting handles to effect a separation of the compression elements.

In testimony that I claim the foregoing as my own, I have hereto affixed my signature in the presence of two witnesses.

TRUMAN DEAN GARD.
